UNITED STATES PATENT OFFICE.

ELMER ANDERSON, OF TUSTIN, MICHIGAN.

SPRING-SEAT ATTACHMENT.

No. 853,616.

Specification of Letters Patent.

Patented May 14, 1907.

Application filed February 8, 1907. Serial No. 356,453.

To all whom it may concern:

Be it known that I, ELMER ANDERSON, a citizen of the United States, residing at Tustin, in the county of Osceola and State of Michigan, have invented certain new and useful Improvements in Spring-Seat Attachments, of which the following is a specification.

My invention contemplates certain new and useful improvements in spring seats for vehicles, and the invention has for its object an improved construction of spring seat whereby the springs may be moved closer together or farther apart so that they will fit different widths of wagon beds.

The invention consists in certain constructions and arrangements of parts hereinafter described and claimed.

For a full understanding of the invention and the merits thereof and also to acquire a knowledge of the details of construction of the means for effecting the result, reference is to be had to the following description and accompanying drawings, in which:

Figure 1 is a side elevation of my improved seat for vehicles; Fig. 2 is a front elevation thereof; Fig. 3 is a bottom plan view of one end portion of the seat; and, Fig. 4 is a detail perspective view of one of the plates employed.

Corresponding and like parts are referred to in the following description and indicated in all the views of the drawings by the same reference characters.

In carrying out my invention, the bowed spring members 1 and 2 are hinged together at their ends in the usual manner and are secured, respectively, to lower and upper supporting bars 3 and 5, the former being provided at its ends with clips or downwardly facing hooks 4 adapted to be placed over the ordinary supporting rails of the vehicle body. The spring members 1 and 2 are rigidly secured to their supporting bars and the upper spring member 2 is screwed or bolted, as shown, to its bar, and the said attaching bolts extend through elongated apertures or slots 6 in the plate 7 which is interposed between the upper supporting bar and the upper spring member, as shown. The plate 7 is provided, preferably at its middle with a lateral extension 8 formed with an aperture 9 and said plate is also

formed at its two ends with sleeves 10 preferably produced by curling the ends of the plate. These sleeves may fit in slight grooves in the upper supporting bar 5, as shown.

A pair of rods 11 pass through the two sleeves 10 and said rods are provided at one end with eyes 12 adapted to receive the threaded shanks 13 of shackle plates 14, the outer ends of which are angular as shown, and are adapted to extend upwardly and over the upper ends of the seat 15 and over a cleat 16 at the end of the seat. This cleat is not essential, but it usually forms the side bar of a seat of this character. The heads of the shackle plates 14 are provided in both of their angular members with holes designed to receive the screws as shown so as to secure the said heads to the ends of the seat.

18 designates nuts that are screwed upon the threaded shanks 13 of the shackle plates 14 at opposite sides of the eyes 12 so as to adjustably secure the shackle plates to the rods 11. The inner ends of the rods 11 extend into the eyes 19 to secure the bolts 20 that pass through apertures formed to receive them in the strap 21, the latter being riveted or screwed to the under side of the seat as shown.

22 designates a screw which is adapted to pass through the hole 9 in the lateral extension 8 of the plate 7 and into the seat from the under side thereof, so as to secure the plate 7 and consequently the springs 1 and 2 and their supporting bars 3 and 5 at the proper point along the rods 11 to effect the proper adjustment of the springs according to the width of the seat.

From the foregoing description in connection with the accompanying drawings, it will be seen that I have provided a very simple construction and arrangement of the parts, whereby the springs at the ends of the wagon seat may be adjusted toward or from each other with respect to the seat, so as to enable seats of different widths to be used and readily applied to the springs. After the parts have been adjusted, they may be rigidly secured together so as to produce a strong and stable structure.

While I have described the spring arrangement and construction at one end of the seat

only, it is, of course, to be understood that the parts are duplicated for the opposite end of the seat.

Having thus described the invention, what is claimed as new is:

1. A vehicle seat construction, comprising a seat, rods connected to the seat and extending underneath the ends thereof, springs provided with upper and lower supporting bars, a plate secured to the upper supporting bar of each spring and slidably mounted on said rods, each plate being provided with a lateral extension, and a fastening device working through said extension and adapted to be secured to the seat, as and for the purpose set forth.
2. A vehicle seat construction comprising a seat, shackle plates secured to the ends of the seat and extending below the same, rods secured at one end to said shackle plates, a strap to which the other ends of said rods are secured, springs provided with upper and lower supporting bars, the upper bars extending between the rods and the lower face of the seat, a plate provided at its ends with

sleeves encircling said rods and slidably mounted thereon, said plate being formed with a lateral extension, and a screw working through said extension and into the seat.

3. A vehicle seat construction, comprising a seat, a pair of shackle plates secured to each end of the seat, a pair of rods for each pair of shackle plates at one end, straps secured to the seat and provided with eye-bolts into which the other ends of the rods extend, springs provided with upper and lower supporting bars, plates interposed between said springs and the upper bars and provided at their outer ends with sleeves slidably mounted on said rods, each plate being provided with a lateral extension, and screws working through said extensions and into the seat.

In testimony whereof I affix my signature in presence of two witnesses.

ELMER ANDERSON. [L. s.]
